PORTABLE HEATER

Robert S. Waters, Lexington, Ohio, assignor to Westinghouse Electric Corporation, East Pittsburgh, Pa., a corporation of Pennsylvania

Filed Dec. 1, 1960, Ser. No. 72,910

6 Claims. (Cl. 34—91)

This invention relates to space or room heaters, more particularly to portable heaters of this type, and has for an object to provide, in combination therewith, novel means for supporting articles to be dried by heat from such heaters.

Another object of the invention is to so arrange both a carrying bar and a drying bar for a portable space heater that each cooperates with the other to promote satisfactory performance of their respective functions.

Briefly, the invention, in a preferred form, utilizes a pair of horizontal bars, maintained in spaced parallel relation by side arms joined at their ends remote from the bars and pivotally connected, adjacent the joined ends, to the heater for limited pivotal movement of the assembled bars and side arms. At one limit of pivotal movement of the assembly one of the bars is positioned above the heater substantially in vertical alignment with the center of gravity of the heater, this bar thus providing a handle or carrying bar for the heater. In this position the other bar is disposed behind the heater adjacent the lower edge thereof, and preferably is releasably latched there. At the other limit of pivotal movement of the assembly the other bar is disposed above and in front of the heater so that fabrics or other articles hung on this bar to dry are positioned in the path of heated air discharged from the heater. This bar is referred to as a drying bar and is retained in its drying position by engagement of the carrying bar with the front of the heater.

The foregoing and other objects are effected by the invention as will be apparent from the following description and claims taken in connection with the accompanying drawings, forming a part of this application, in which:

FIG. 1 is a perspective view of a portable room heater incorporating the invention;

FIG. 2 is an end elevational view of the structure shown in FIG. 1;

FIG. 3 is a view similar to FIG. 2, but showing the bar assembly in a different position; and,

FIG. 4 is an enlarged fragmentary sectional view taken along the lines IV—IV of FIG. 3, looking in the direction indicated by the arrows.

The space or room heater 10, illustrated in the drawing, includes a base 11 on which is secured a casing 12, the latter including a top wall 13, side walls 14 and a rear wall 16 and having an open front 17 protected by conventional grille work 18. Preferably, the base 11 is provided with a plurality of feet 19 to space the base from any supporting surface on which the heater may be placed, such as a floor, table top, shelf or the like.

The casing 12 houses the usual heating element 21, surrounded on the four sides and the rear by a reflector 22 for directing radiant and reflected heat forwardly through the open front 17 of the casing. A fan 23 may be housed in the base 11 for drawing air in through the bottom of the base and forcing it upwardly and forwardly around the outside of the reflector and exhausting it through a peripheral space between the reflector forward edge and the casing walls.

The construction described heretofore may be considered as conventional, applicant's contribution relating to the combination with such a heater of the novel bar

2

assembly, indicated in its entirety by the reference character 25.

This bar assembly 25 includes a carrying bar 26 and a drying bar 27 disposed in horizontal parallel spaced relation and maintained in such relation by side arms 28 integral with the ends of the carrying bar 26 and side arms 29 integral with the drying bar 27.

The side arms 28 and 29 are permanently joined, at their ends remote from their respective bars, as at 31, by welding, brazing or the like. It will be apparent from consideration of FIGS. 1, 2 and 3 that the side arms 28 lie in a plane displaced a substantial degree from the plane in which the side arms 29 are disposed.

The terminal portions of the side arms 28, adjacent the welded connection between the side arms 28 and 29, are disposed in a horizontal plane, parallel to the bars 26 and 27 and serve as journals for pivotal mounting of the bar assembly 25. Such pivotal mounting of the bar assembly is effected by disposition of the journal portions 32 in aligned openings 33 in the casing side walls 14. The journal portions 32 are retained in the bearing openings 33 by means of conventional toothed lock washers 34 engaging the inner ends of the journaled positions 32. Washers 35 are positioned on the journal portions 32 between the casing side walls 14 and the joined side arms 28 and 29 to prevent rubbing of the arms against the side walls.

With the bar assembly 25 journalled in the casing side walls for pivotal movement with respect to the heater, the assembly may be pivoted between the two limits of movement illustrated in FIGS. 2 and 3.

In the position illustrated in FIG. 3, the carrying bar 26 is positioned substantially directly above the center of gravity of the complete heater 10 and the drying bar 27 is disposed adjacent the rear wall 16 of the heater, in close proximity to the bottom edge of the base 11, where it is substantially concealed when the heater is viewed from the front. A resilient clip 36, carried by the base 11, cooperates with the drying bar 27 to retain the latter in the position shown in FIG. 3.

When it is desired to utilize the drying bar 27, the bar assembly 25 is pivoted to the position illustrated in FIG. 2, in which position the drying bar 27 is disposed horizontally above and forwardly of the open front 17 of the heater where fabric articles or other articles of wearing apparel or the like which are to be dried when hung on the bar 27 will be positioned in the flow path of hot air discharged through the open front of the heater, this flow path being indicated by the solid arrows in FIG. 2.

The weight of articles hanging on the drying bar 27 when the latter is in the drying position of FIG. 2 would tend to pivot the bar assembly counterclockwise were it not for the fact that the carrying bar 26 engages the front of the casing 12 to retain the drying bar in its drying position.

The above description of the operation of the two bars 26 and 27 renders obvious the necessity for disposing side arms 28 and 29 in angularly-disposed planes.

It is believed apparent from the above description that applicant has provided a unique bar assembly provided for both ready manual transportation of the portable heater 10 and convenient drying of articles by use of the heat discharged by the heater.

While the invention has been shown in but one form, it will be obvious to those skilled in the art that it is not so limited, but is susceptible of various changes and modifications without departing from the spirit thereof.

What is claimed is:

1. In combination with a portable space heater, a pair of bars, means connecting said bars in spaced parallel relation, means mounting said bars for pivotal movement relative to the heater between a first position where

one of said bars overlies the heater approximately above the center of gravity of the latter and the other bar abuts the heater to limit pivotal movement of the bars in one direction and a second position in which said other bar is disposed above and generally forwardly of the heater and the said one bar abuts the heater to limit pivotal movement of the bars in the opposite direction.

2. In combination with a portable space heater, a carrying bar and a drying bar, means fixedly connecting said bars in spaced parallel relation, means mounting said connected bars for pivotal movement relative to the heater between a first position where the carrying bar overlies the heater approximately above the center of gravity of the latter and the drying bar abuts the heater to limit pivotal movement of the bars in one direction and a second position in which said drying bar is disposed above and generally forward of the heater and the said carrying bar abuts the heater to limit pivotal movement of the bars in the opposite direction.

3. In a portable space heater, a casing, a heating element housed in said casing, a fan for passing air over said heating element to heat said air, means for directing the heated air outwardly from said casing, a bar assembly including a carrying bar and a drying bar disposed in spaced parallel relation, and means mounting said bar assembly on said casing for pivotal movement between a carrying position in which said carrying bar is disposed above the casing and the drying bar is disposed adjacent the casing and a drying position in which the drying bar is so disposed in spaced relation with respect to the casing that fabric articles hanging on said drying bar are positioned in the path of heated air from the casing.

4. In a portable space heater, a casing, a heating element housed in said casing, a fan for passing air over said heating element to heat said air, means for directing the heated air outwardly from said casing, a bar assembly including a carrying bar and a drying bar disposed in spaced parallel relation, and means mounting said bar assembly on said casing for pivotal movement between a carrying position in which said carrying bar is disposed above the casing and the drying bar is disposed adjacent the casing and a drying position in which the drying bar is so disposed in spaced relation with respect to the casing that fabric articles hanging on said drying bar are positioned in the path of heated air from the casing and the carrying bar engages the casing to prevent pivotal movement of the bar assembly as a result of the weight of articles on the drying bar.

5. In a portable space heater; a casing closed at the top, back and ends and open at the front; a heating ele-

5 ment housed in said casing; a fan for moving air into said casing for heating by said heating element and for discharging the heated air through the open front of the casing; a bar assembly including a carrying bar, a drying bar and side members connecting said bars in parallel spaced-apart relation; and means associated with said side members for pivotally mounting the bar assembly on the casing for movement between a carrying position where the carrying bar is disposed in parallel spaced relation to the casing top and lies approximately in the vertical transverse plane which contains the center of gravity of the heater with the drying bar disposed behind the heater, and a drying position where the drying bar is disposed above and forwardly of the casing whereby fabric articles hanging on said drying bar are disposed in the path of heated air discharged through the open front of the casing and the carrying bar abuts the heater to maintain said drying bar in said drying position.

6. In a portable space heater; a casing closed at the top, back and ends and open at the front; a heating element housed in said casing; means for moving air into said casing for heating by said heating element and for discharging the heated air through the open front of the casing; a bar assembly including a carrying bar, a drying bar and a pair of side arms for each bar, the side arms of each pair being fixed at one end to the ends of their respective bars and having their free ends joined to the corresponding ends of the other pair, said pairs of side arms lying in different planes; and means associated with each pair of joined side arm ends for pivotally mounting the bar assembly on the heater casing for limited movement between a carrying position where the carrying bar is disposed horizontally above the heater and the drying bar is disposed adjacent the casing, and a drying position where the drying bar is disposed horizontally above and in front of the casing whereby articles hanging on said dry bar are disposed in the path of heated air discharged through the open front of the casing and the carrying bar abuts the heater to maintain the drying bar in its drying position.
